SCOOTER SLED

Steve Phillips, Uniontown, Pa.

Application December 5, 1934, Serial No. 756,133

4 Claims. (Cl. 280—23)

This invention relates to an improved child's sled of the scooter type wherein front and rear runners support a platform on which the user may stand with one foot while using the other foot to propel the device, and wherein the front runner is carried by a steering post by which the user may steady himself upon the platform and at the same time properly steer the sled.

The primary object of the present invention is to provide a scooter sled of the above kind which is extremely simple and durable in construction, inexpensive to manufacture, and entirely satisfactory in use.

More particularly, the present invention consists in the novel form, combination and arrangement of parts hereinafter more fully described, shown in the accompanying drawing and claimed.

In the drawing:

Figure 1 is a side elevational view, partly broken away and in section, of a scooter sled constructed in accordance with the present invention.

Figure 2 is a top plan view thereof.

Figure 3 is a vertical transverse section on line 3—3 of Figure 1 with the sled support in vertical operative position; and

Figure 4 is a fragmentary perspective view showing the front end of the platform and the sled stand or support carried thereby.

Referring more in detail to the drawing, the present invention includes a pair of spaced longitudinal frame bars 5 having the forward ends 6 thereof turned upwardly and rigidly connected intermediate their ends by spacing brackets 7. Rigidly secured upon the horizontal intermediate portions of longitudinal frame bars 5 is a sheet metal platform 8 having a downturned marginal flange 9 which is slotted at the front and rear ends of platform 8 as at 10 to receive the adjacent portions of the frame bars 5 and thereby prevent lateral relative displacement between the frame bars and the platform. Thus, the platform is effectively secured in place merely by riveting the latter centrally to the spacing brackets 7 as at 11.

The rear ends of frame bars 5 are connected by a transverse bolt or shaft 12. The sled further includes a rear runner 13 preferably formed T-shape in cross section with the flat portion at the bottom, and the forward end of this runner is turned upwardly and bolted as at 14 to the under side of platform 8 near the rear end of the latter. The runner 13 is carried by a suitable support consisting of a strip of sheet metal pro-

vided with a central cylindrical fold 15 located between and spacing the rear ends of frame bars 5 and through which the bolt 12 extends, the ends of the strip of sheet metal extending downwardly from the fold 15 to provide diverging legs 16 which taper narrower in width downwardly and have their lower ends folded longitudinally as at 17 to resist bending and to fit over the upstanding central rib of runner 13 where they are riveted to such rib as at 18.

The sled further includes a front runner 19 which is also preferably formed T-shape in cross section with the flat portion at the bottom and which is carried by a support similar in construction to the support for the rear runner 13 15 and including the central cylindrical fold 15a, the downwardly diverging legs 16a having their lower ends longitudinally folded as at 17a and riveted as at 18a to the upstanding central rib of runner 19.

The front runner 19 and its support is carried by a steering post composed of spaced substantially parallel bars 20 rigidly connected at their upper ends by a transverse handle bar 21 and at their lower ends by a transverse bolt or shaft 22 which extends through the cylindrical central fold 15a of the front runner support. It will of course be understood that this fold 15a is located between the lower ends of the bars 20 forming the steering post so as to space said ends thereof. The steering post 20 is pivotally connected intermediate its ends to the forward ends of frame bars 5 by means of a suitable steering knuckle 23 arranged to dispose the steering post at a slight forward and downward inclination and to enable said steering post to swing about a similarly inclined axis adjacent and directly at the rear of said steering post. The forward end of front runner 19 is extended upwardly and rearwardly where its upper terminal is rigidly fastened to the intermediate portion of a bracket or cross bar 24 rigidly connecting the bar members 20 of the steering post at a point directly below the steering knuckle 23. Obviously, by bolting the rear runner 13 to the platform 8 as at 14, and by fastening the front runner 19 to the bracket 24, the runners together with their supports are prevented from rotating about the shafts 12 and 22, and a very rigid and durable construction is had.

In use, the child stands with one foot on the platform 8 and utilizes the other foot to propel the sled over the surface of the snow or ice, simultaneously grasping the handle bar 21 with both hands so as to steady himself upon the platform.

8 and to steer the sled. When the sled gains the desired momentum, the user may of course place both feet upon the platform 8 until further propulsion is necessary.

5 It is desirable to provide a stand or support for maintaining the present sled in an upright position when not in use, it being apparent that the sled will not remain upright of its own accord because involving only two runners arranged 10 in tandem relation. For this purpose a stand or support is provided including a U-shaped member 25 straddling the front end portion of platform 8 and having its legs pivoted intermediate their ends to the flange 9 of said platform 8 at opposite sides of the latter as at 26. This stand or support is formed by a suitably bent metallic rod of a resilient nature which permits lateral relative yielding of the legs of said stand 25, and said legs are allowed limited outward movement on 15 its pivot pins at 26, for a purpose which will presently become apparent. Provided on the flange 9 of platform 8 directly beneath the pivot pins 26 are notched keepers 27 having cam edges 28 rearwardly of the notches thereof. Thus, 20 when the stand or support 25 is swung from the horizontal inoperative position of Figure 1 to the dotted line vertical position of the same figure or the full line position of Figure 4, the legs of said stand or support 25 will ride along the cam edges 28 so that the legs will be spread apart slightly until they register with the notches of keeper plate 27, whereupon said legs will resiliently 25 spring into said notches for maintaining the stand or support 25 in such vertical or operative position with the lower free ends of the legs thereof engaged with the ground. Naturally, in order to return the stand or support 25 to its inoperative position it is simply necessary to manually 30 spring the legs thereof apart and out of the notches of keeper plates 27, and to then swing the stand or support about its pivot pins 26 to the horizontal position of Figures 1 and 2. The legs of the stand or support will then be disposed directly above the keepers 27 so that the stand or support will be retained by the latter in its horizontal inoperative position until manually 35 shifted therefrom to operative position. It will be noted that the stand or support 25 is so located that the intermediate portion thereof 40 will extend across the frame bars 5 directly in front of the platform 8 when said stand or support is inoperatively disposed, the stand being at such time entirely out of the way and snugly embracing the sides and front end of the platform at such time. However, in order to facilitate manual actuation of the stand or support 25 to shift it from or to operative position, its intermediate portion is centrally outwardly offset 45 as at 29 to provide a hand grip which may be readily grasped. With the stand or support 25 vertically disposed as in Figure 4, the lower ends of its legs will engage the ground at spaced points and at opposite sides of the platform 8 so that the sled will be effectively sustained in a vertical 50 position when at a standstill.

The platform 8 may have spaced rearward extensions 30 on opposite sides of its rear end between which the user may engage his heels so that the user's foot will be prevented from slipping laterally off of the platform. Also, the runners 13 and 19 may have central longitudinal ribs 31 and 32, respectively, to guard against lateral slipping of the sled.

From the foregoing description, it will be readily seen that the present invention provides a

scooter sled which will be entirely satisfactory in use and which is extremely simple and durable in construction as well as particularly adapted for ready and economical quantity production. Minor changes in details of construction illustrated and described are contemplated within the spirit and scope of the invention as claimed.

What I claim as new is:

1. A scooter-sled comprising a pair of spaced longitudinal frame bars having the forward ends thereof turned upwardly, a platform secured upon the intermediate portions of said frame bars, a shaft connecting the rear ends of said frame bars, a rear runner support formed of a strip of sheet metal bent to provide a central cylindrical fold 15 arranged between said frame bars and through which said bolt extends, said strip of sheet metal further providing legs extending downwardly from said cylindrical fold in diverging relation and having the lower ends thereof longitudinally 20 folded, a rear runner of T-shape in cross section providing a central upstanding rib straddled by the longitudinally folded lower ends of said legs and rigidly secured thereto, said rear runner having an upwardly turned forward end rigidly secured to the under side of said platform near the rear end of the latter, a steering post pivotally connected intermediate its ends to the forward ends of said frame bars, a front runner, and a support for said front runner carried by 25 the lower end of said steering post.

2. A scooter-sled comprising a pair of spaced longitudinal frame bars having the forward ends thereof turned upwardly, a platform secured upon the intermediate portions of said frame bars, a shaft connecting the rear ends of said frame bars, a rear runner support formed of a strip of sheet metal bent to provide a central cylindrical fold 35 arranged between said frame bars and through which said bolt extends, said strip of sheet metal further providing legs extending downwardly from said cylindrical fold in diverging relation and having the lower ends thereof longitudinally 40 folded, a rear runner of T-shape in cross section providing a central upstanding rib straddled by the longitudinally folded lower ends of said legs and rigidly secured thereto, said rear runner having an upwardly turned forward end rigidly secured to the under side of said platform near the rear end of the latter, a steering post pivotally 45 connected intermediate its ends to the forward ends of said frame bars, a front runner, and a support for said front runner carried by the lower end of said steering post, said platform being of sheet metal and provided with a downwardly 50 turned marginal flange slotted at the front and rear ends of the platform to receive the adjacent portions of the frame bars.

3. A scooter-sled comprising a pair of spaced longitudinal frame bars having the forward ends thereof turned upwardly, a platform secured upon the intermediate portions of said frame bars, a shaft connecting the rear ends of said frame bars, a rear runner support formed of a strip of sheet metal bent to provide a central cylindrical fold 60 arranged between said frame bars and through which said bolt extends, said strip of sheet metal further providing legs extending downwardly from said cylindrical fold in diverging relation and having the lower ends thereof longitudinally 65 folded, a rear runner of T-shape in cross section providing a central upstanding rib straddled by the longitudinally folded lower ends of said legs and rigidly secured thereto, said rear runner having an upwardly 70 turned forward end rigidly secured to the under side of said platform near the rear end of the latter, a steering post pivotally connected intermediate its ends to the forward ends of said frame bars, a front runner, and a support for said front runner carried by the lower end of said steering post, said platform being of sheet metal and provided with a downwardly 75 turned marginal flange slotted at the front and rear ends of the platform to receive the adjacent portions of the frame bars.

turned forward end rigidly secured to the under side of said platform near the rear end of the latter, a steering post pivotally connected intermediate its ends to the forward ends of said frame bars, a front runner, and a support for said front runner carried by the lower end of said steering post, said steering post including spaced bars rigidly connected at their upper ends by a transverse handle bar and at their lower ends by a transverse bolt, said second-named front runner support being constructed similar to the rear runner support with its central cylindrical fold arranged between the lower ends of said bars of the steering post and having the last-named bolt extending therethrough, said front runner being

of T-shape in cross section to provide a central upstanding rib to which the lower ends of the front runner support are rigidly secured, a bracket rigidly connecting the bars of the steering post beneath the pivotal connection of the steering post with the longitudinal frame bars, said front runner having an upwardly and rearwardly turned forward end rigidly secured to said bracket.

4. A scooter-sled as specified in claim 1, where-
in the platform is provided with spaced rearward extensions on the rear end thereof between which the user may engage a heel of one foot to prevent lateral slipping of such foot off of the platform.

STEVE PHILLIPS. 15
